CLAIM

The ornamental design for a hand-held container, as shown and described.

DESCRIPTION

FIG. 1 is a perspective view of hand-held container, as viewed from the top, rear, and right side thereof;

FIG. 2 is a top plan view of a hand-held container of FIG. 1; FIG. 3 is a front elevational view of a hand-held container of FIG. 1;

FIG. 4 is a right side view of a hand-held container of FIG. 1;

FIG. 5 is a left side view of a hand-held container of FIG. 1;

FIG. 6 is a rear elevational view of a hand-held container of FIG. 1; and,

FIG. 7 is a bottom plan view of a hand-held container of FIG. 1.

The dashed lines in FIG. 1–7 depict unclaimed portions of the design. The dashed lines and the structure they depict form no part of the claimed design. The dash-dot-dash lines in FIGS. 1, 2, 4, 6 and 7 define the boundary of the claimed design and form no part of the claimed design.

UNITED STATES PATENT AND TRADEMARK OFFICE
Certificate

Patent No. D. 604,471 S

Patented: November 17, 2009

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Mark W. Bergman, Minnetonka, MN (US); Matthew V. Leyden, St. Paul, MN (US); and Jeffrey B. Waffensmith, North Oaks, MN (US).

Signed and Sealed this Second Day of July 2013.
